(57) **CLAIM**

The ornamental design for an earphone, as shown and described.

DESCRIPTION

FIG. 1 is a perspective view of the front, top, and left side of an earphone showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective reference view in use thereof.

The broken line showing of the earphone is included for the purpose of illustrating portions of the earphone and forms no part of the claimed design.

1 Claim, 8 Drawing Sheets
